UNITED STATES PATENT OFFICE.

ROBERT B. WOOLVERTON, OF WASHINGTON, DISTRICT OF COLUMBIA.

TRANSMISSION OF RADIOSIGNALS EMPLOYING UNDAMPED WAVES.

Application filed July 25, 1921. Serial No. 487,247.

To all whom it may concern:

Be it known that I, ROBERT B. WOOLVERTON, citizen of the United States, and residing at Washington, District of Columbia, have invented certain new and useful Improvements in the Transmission of Radiosignals Employing Undamped Waves, of which the following is a specification.

This invention relates to improvements in radio transmission apparatus wherein a generator of persistent or undamped oscillations, such as an arc generator, high frequency alternator or other source of energy is employed, and has for an object, the provision of transmitting apparatus of such arrangement as will permit of rapid fluctuations of the signal energy with the consequent production of sharp rapid signals at a receiving station, a result impossible to be obtained satisfactorily by use of heretofore prevalent apparatus.

Other objects will be in part obvious and in part pointed out hereinafter.

In the employment of generators such as the arc and high frequency alternator, the method heretofore employed has been to connect the source of persistent oscillations directly in the antenna circuit in order to make the over-all efficiency as high as possible. The interruptions in the antenna circuit were then produced by a variety of methods such as by varying the inductance in the antenna circuit by short-circuiting the turns, or by connecting across the generator an oscillatory circuit having a lower resistance than the antenna circuit, so that by closing this oscillatory or local "tank" circuit by means of a key, practically all of the generated radio frequency energy is diverted from the antenna circuit to the "tank" circuit. There are other means either employed, or discarded, but all so far devised are unsatisfactory, because generally the factors, necessary to be varied to produce variations in the antenna current, have been too great, and tend therefore to prevent rapid transmission.

Because of the constant advance in receiving apparatus, less energy need now be generated in the antenna circuit to cover a given distance. Therefore, the over-all efficiency of a generator of radio frequencies is not paramount, this consideration giving ground to that of rapid transmission, a condition accomplished through the instrumentalities of my invention.

It is therefore proposed to provide means for destroying resonance between the antenna or radiating circuit and the closed or generating circuit in such a manner as to not only obviate any great variation in the elements themselves, but also to obviate the interruption of energy in the resonance destroying means.

In order that the invention and its mode of application may be readily understood by persons skilled in the art, I have, in the accompanying illustrative drawings, and in the detailed following description based thereon, set forth several embodiments of the same.

In these drawings, Figure 1 is a diagrammatic view of one form of the circuit provided with intelligence forming means;

Figure 2 is a fragmentary diagrammatic view of the circuit wherein an electro-static connection is employed in lieu of the inductive arrangement shown above, and

Figs. 3, 4 and 5 are fragmentary diagrammatic views showing modified forms of intelligence forming means.

Having more particular reference to the drawings, in connection with which like characters of reference will designate corresponding parts thereof, 1 indicates the driving circuit of a transmitting set of undamped waves connecting a source of energy 2, a generator 3 which may be either an arc generator as shown herein, a high frequency alternator, or any other generator of persistent oscillations such as conditions or preference may dictate, and a choke coil 4, the latter serving to prevent the return of radio currents to the source 2.

Shunted about the generator 3 is a tuned oscillatory circuit comprising conductors 5 connected inductively as at 6 to the antenna circuit 8, while a condenser 7 is interposed in one of the said conductors for an obvious purpose. Exact resonance is produced in the two circuits so coupled, namely, the oscillatory and the antenna circuits, which, because of its extreme accuracy, due to the employment of persistent oscillations, may be easily destroyed to completely prevent, or to prevent to a large degree, the transfer of energy from the generator circuit to the antenna circuit, at a desired frequency. A very slight variance of either the capacitance or of the inductance in such generator or antenna circuits will destroy exact resonance and by consequence the current

in the antenna circuit will either cease entirely, or will be sufficiently reduced to produce the necessary signal at the receiving station.

5 As means for effecting the production of signals, or more broadly, intelligence, a relatively small capacitance 9 is shunted about the capacitance 7, and is so constructed as to permit of appreciable variation of its 10 individual capacitance by a minimum of adjustment of one or of both of its elements. The adjustment of the capacitance 9 is affected through the medium of a solenoid 10, having the armature thereof connected 15 to but insulated from, as at 11, one of the elements of the capacitance 9, which, as will be understood, is movable. The coil of the solenoid is connected in a circuit 12, having a key 13, interposed therein, which, upon 20 being opened and closed will cause variation in the positioning of the solenoid armature, thereby causing rapid variations in the relative positioning of the capacitance element 9 with the resultant rapid variation 25 of frequency in the generator circuit whereby to produce corresponding rapid signals at a receiving station, due to the alternate establishment and destruction of resonance between the generator and antenna circuits.

Instead of inductively coupling the oscillatory circuit to the antenna system, it is to be also understood that the inductances 6' and 8' as shown in Figure 2, may be electrostatically connected by the condensers 14 and 15, which, upon adjustment of the elements of either thereof, will permit of rapid fluctuations in the antenna current by reason of the destruction or partial destruction 40 of the exact resonance normally existing between the generator and antenna circuits, thus producing a series of corresponding rapid signals at the receiving station.

In Figure 3, I have shown a slightly modified form of employing intelligence forming means, employing herein the coils of a variometer indicated at 16 and connecting such coils in series with one side of the oscillatory circuit formed by the conductors 5. An intelligence forming key 13' is interposed in the circuit 12' which in turn, includes the circuit 10' whose armature is connected to but insulated from an arm 17, having connection with one of the coils 16 of the variometer. Thus, upon movement of the solenoid armature, that coil of the variometer connected to the arm 17 will have its relative positioning with respect to the opposite coil varied, and in consequence, the total inductance of the generator circuit including variometer inductors 16, inductor 6' and the conductors 5, will be altered accordingly, whereby to destroy exact resonance between the generator circuit and the antenna system 8, for sufficiently reducing current in the an-

tenna circuit to produce the desired signal at the receiving station.

Instead of the arrangements shown in the preceding figures, it is to be also understood that by placing the resonance destroying means in the so-called oscillatory circuit, the same may be as advantageously arranged in the antenna circuit of the apparatus as shown in the Figure 4. Herein the oscillatory circuit is identified at 5' and is coupled, inductively, at 6' to the antenna circuit 8' which latter circuit has the coils of a variometer 16' connected in series therein as at 18; an arm 17' extends from one of said coils and has the armature of a solenoid 10' connected thereto, whereby with energization of the solenoid, the arm 17' will be caused to accordingly change the relative positioning of the coils of the variometer. An intelligence forming circuit 12', corresponding to the circuits 12 and 12', is provided the solenoid 10', and obviously will afford means for effecting the shifting of the arm 17'.

From the foregoing, it is to be understood that with the change in the relative positioning of the several coils of the variometer, the capacitance of the antenna circuit will be varied, and by consequence, resonance as between the same and the oscillatory circuit will be destroyed. Thus, the forming 95 of intelligence or signals by this intermittent destruction of resonance between the oscillatory and antenna circuits, is rendered possible.

In the Figure 5, I have disclosed another arrangement of means for destroying resonance between the oscillatory and antenna circuits, wherein the antenna circuit 8' has a capacitance 19, arranged in the same, and about which a second capacitance 9' is shunted. To the movable element of the capacitance 9', the armature of the solenoid 10' is connected, being insulated therefrom as at 11'. The terminals of the solenoid 10' are connected to the opposite sides of an intelligence forming circuit 12' corresponding to the circuit 12' and therefore, with closing of the key in said circuit, the solenoid 10' will be energized, thus varying the positioning of the movable element of the capacitance 9' with relation to the fixed element thereof whereby to vary or change the capacitance of the antenna circuit 8' and consequently destroy resonance as between said antenna circuit and the oscillatory circuit in order that the forming of intelligence or signals may be practically effected.

Manifestly, the arrangements shown throughout are capable of considerable modification, and such modification as is within the scope of my claims, I consider within the spirit of my invention.

I claim:

1. In radio transmitting apparatus, for

undamped waves, a tuned oscillatory circuit shunted about the generator of said transmitting apparatus, an antenna circuit electrically connected to the tuned oscillatory circuit, said oscillatory and antenna circuits being in exact resonance, a capacitance shunted about the capacitance of the tuned oscillatory circuit, and means for varying the relative positioning of the elements of said first capacitance whereby to destroy resonance between the oscillatory and antenna circuits, at times, whereby the energy in said antenna circuit is substantially interrupted.

16 2. In radio apparatus for transmitting undamped waves, a tuned oscillatory circuit shunted about the generator of said apparatus, an antenna circuit electrically coupled to the tuned oscillatory circuit, said oscillatory and antenna circuits being in exact resonance, a capacitance shunted about the capacitance of the tuned oscillatory circuit having one of its elements movable, a solenoid, the armature of said solenoid having insulated connection with said movable element and the first mentioned capacitance, and an intelligence forming circuit coupled to said solenoid for energizing the same whereby to vary the relative positioning of the elements of the first mentioned capacitance for destroying the exact resonance between the oscillatory and antenna circuits, as and for the purpose set forth.

R. B. WOOLVERTON.
